(57) **CLAIM**

The ornamental design for a portion of a shoe as shown and described.

DESCRIPTION

FIG. 1 is a front right perspective view of an embodiment of a portion of a shoe showing our new design; FIG. 2 is front view of the design shown in FIG. 1; FIG. 3 is a rear view of the design shown in FIG. 1; FIG. 4 is a right side view of the design shown in FIG. 1; FIG. 5 is a left side view of the design shown in FIG. 1; FIG. 6 is a top view of the design shown in FIG. 1; and, FIG. 7 is a bottom view of the design shown in FIG. 1. The broken lines shown in the figures are included for the purpose of illustrating portions of the portion of the shoe and form no part of the claimed design. The dash-dot-dash lines illustrate unclaimed boundary lines and form no part of the claimed design. The areas within the solid lines and the dash-dot-dash lines form the claimed design. The figures include textured portions, which is designed to show a stitched fabric of the design.
